UNITED STATES PATENT OFFICE.

ROY G. BACHMAN, OF CHICAGO, ILLINOIS, ASSIGNOR TO AMORITE PRODUCTS CORPORATION, OF CHICAGO, ILLINOIS, A CORPORATION OF ILLINOIS.

BUILDING MATERIAL.

Application filed March 16, 1922. Serial No. 544,185.

To all whom it may concern:

Be it known that I, Roy G. BACHMAN, a citizen of the United States, residing at Chicago, in the county of Cook and State 5 of Illinois, have invented certain new and useful Improvements in Building Material, of which the following is a specification.

The present invention relates to building material.

10 More particularly the present invention relates to material which may be fastened to the scantling of a house, either upon the interior or exterior of said house, for providing weather-proofing means and means 15 for supporting plaster, stucco, or other plastic wall covering material.

An object of the present invention is to provide building material which comprises weather-proofing material for houses, and 20 also comprises means for holding plaster, stucco, or other plastic wall covering.

25 A further object is to provide building material which will avoid the necessity for using the lath which is commonly employed 25 for holding plaster, stucco, or the like.

30 A further object is to provide building material having good heat and sound insulating qualities and which forms efficient means for holding plastic wall coverings.

35 A further object is to provide building material which may be supplied in pieces convenient for handling, which may be readily shipped, and which requires only a minimum of skill in applying to the scantling of a house.

Further objects will appear as the description proceeds.

Referring to drawings—

40 Figure 1 represents in front elevation one embodiment of the present invention applied to the scantling of a house;

45 Figure 2 is a view in side elevation illustrating a modified embodiment of the present invention applied to the scantling of a house;

Figure 3 is a sectional view taken along the line 3—3 of Figure 1;

Figure 4 is a sectional view taken along the line 4—4 of Figure 1.

50 The present invention contemplates the use of relatively stiff board having lath means attached thereto. Said board may be chosen from a great variety of materials including composition or paper, or may be

strawboard, and for certain constructions 55 corrugated board will be preferred. Said board and the lath means will preferably be covered with weather-proofing material and will be attached to the scantling of a house. The material will be supplied in 60 dimensions for convenient handling and is readily adaptable to attachment by staples or other holding means. The lath means referred to will provide means for holding plaster, stucco, or other wall covering material. One or more layers of board may be supplied, depending upon the choice of 65 the user.

The upright scantlings of a house are indicated by the numerals 1—1. Referring to 70 Figures 3 and 4, it will be apparent that the illustrated embodiments of the present invention show two thickness of corrugated board. Referring to said figures, it will be noted that on the side of the scantling 75 marked "Outside" two corrugated members 3—3 are provided, having the three facing sheets 4—4. On the side of the scantling marked "Inside," however, only two facing sheets 4—4 are provided. The member 3 80 distant from the scantlings may have one of the facing sheets 4—4 omitted for the purpose of presenting a corrugated surface to the plaster in a manner which will be referred to hereinafter. Referring to the 85 layers of corrugated material illustrated in Figures 3 and 4, on the side of the scantlings marked "Outside," it will be noted that said 90 layers are provided with a layer of lath means 5. Said lath means may take any of a great variety of forms, being illustrated 95 as comprising relatively heavy furring wires 6—6 and cross wires 7—7 which may be welded or otherwise united to said furring wires 6—6. The lath means 5 may be attached to the layers of corrugated board by means of stitches 8—8, best illustrated in Figures 1 and 3. Strips 9 of relatively thin, tough material, such as cloth, may be provided on the side of the layers of corrugated 100 board opposite to the lath means 5 for the purpose of preventing said stitches 8—8 from pulling through. Said strips 9 also increase the stiffness of the board.

The composite sheets of stiff board and lath means will preferably be supplied in rectangular shapes. The lines constituting the side boundaries of one of said sheets are 105

indicated by the numerals 10—10 in Figure 1. In order to provide an interlock between adjacent sheets of the building material according to the present invention, 5 the wires 7—7 may be extended laterally beyond one of said boundaries 10, as indicated by the numerals 11—11 in Figure 1 for the purpose of overlying the adjacent furring wires 6 on the next sheet of material. Similar construction may be provided along the top or bottom boundary as indicated by the numerals 11'—11'. By this construction, continuity of the holding means for the plastic material is provided. 10 15 The fabricated building material comprising the layers of board and the lath means 5 is attached to the scantling by means of staples 12—12. Stucco or other plastic material, indicated by the numeral 13, may 20 be applied to the outside and will firmly grip the lath means 5.

Referring now to the embodiment of the present invention which is illustrated in connection with the inside of the house, it 25 will be noted that the board, minus one of the flat facing sheets 4, is faced with wire lath means 14, which may be of the form generally spoken of as "chicken wire," or of any other preferred form. Said lath 30 means 14 will be fastened to the layers of corrugated board by means of stitches 15—15, the fabricated building material being fastened to the scantling by means of the staples 12—12. Plaster 16 may be applied 35 to the inside of the house and will firmly grip the lath means 14. The fact that the layer of corrugated board adjacent to said lath means is not faced with a flat sheet but with a corrugated sheet will permit the 40 firm engagement of said plaster with the lath means 14 without the provision of any added furring pieces. For the reason stated, the construction illustrated for the interior of the house may be referred to as self-furring. 45

It will be clear that the embodiment of the present invention illustrated in connection with the inside of the house may be used on the outside as well, if preferred, and 50 that the embodiment illustrated in connection with the outside of the house will be equally applicable to both interior and exterior work. The building material according to the present invention will be weather-proof, whereby to prevent ingress of rain 55 or snow. The corrugated board will provide air spaces whereby the building material according to the present invention will have very good heat and sound insulating properties. The structure is cheap to 60 manufacture and is very easily handled, and persons with only a minimum of skill will have no difficulty in mounting same in a secure manner upon the scantling of a house. 65 Furthermore, the lath means may be of

metal and will have valuable functions in reinforcing the plastic material applied thereto. The relatively stiff board will ensure plane surfaces and will protect against the loss of plastic material which is so common in present practice. 70

It may be stated that the term "stiff" or "relatively stiff" as applied to the board used in the practice of the present invention is to be construed to refer to such stiffness as will result in a substantially flat surface when said board is applied to scantlings spaced apart the distances commonly found in practice, which distances may be said to range from 12 to 24 inches. 75 80

It will be noted from an inspection of the drawings that the corrugations of the backing member are arranged preferably at right angles to the upright scantlings 1—1, that is to say, the corrugations are arranged 85 horizontally, whereby circulation of air in a vertical direction through said corrugations is prevented. It will be noted also that the building material is substantially imperforate, the holes necessary for the 90 stitches 8—8 and staples 12—12 being filled up by said stitches or staples.

In the claims forming part of this specification, the term "furring means" is intended to be broadly construed to cover the 95 furring wires 6; or the corrugated board 3, minus one of its facing sheets 4, which is illustrated in connection with the lath means 14 for interior construction, or other equivalent constructions which may be preferred. 100

The described embodiments have been chosen merely for the purpose of illustration. Many modifications will occur to those skilled in the art. It is intended in this patent to cover all such modifications 105 that fall within the scope of the invention as defined by the appended claims.

I claim:

1. Building material comprising corrugated board, structure having a plane surface lath means arranged side by side therewith, and means for permanently fastening said board and lath means together, said board being provided with relatively thin, tough members engaging said fastening means for preventing said fastening means from tearing through said board. 110 115

2. Building material comprising corrugated board having flat facing sheets on its opposite sides, lath means placed on the outside of said material side by side with one of said facing sheets, said lath means having furring functions whereby plastic material may grip around said lath means, said corrugated board with its flat facing sheets 120 125 providing a cellular structure having insulating qualities and being sufficiently stiff to withstand the pressure used in applying plaster thereto.

3. Building material comprising a plane 130

- surfaced backing member having lath means permanently secured thereto in the plane surface thereof, said backing member comprising a relatively stiff unit whereby to provide a firm backing for plaster in building construction without the use of sheathing boards, said lath means providing plastic material gripping means spaced from said backing member.
4. Building material comprising a plane surfaced backing member having lath means permanently mounted thereon on the plane surface thereof, means for attaching said lath means to said backing member, said backing member and securing means providing a substantially imperforate structure, said backing member comprising a unit sufficiently stiff to withstand the pressure used in applying plaster whereby to provide a firm backing for said plaster in building construction without the use of sheathing boards.
5. Building material comprising a backing member sufficiently stiff to constitute the siding of a building, and lath means mounted upon one side of said backing member, said lath means comprising furring wires, and cross wires mounted upon said furring wires, said backing member being a parallelogram in outline and having furring pieces adjacent to opposite edges thereof, said cross wires extending beyond the boundaries of said backing member a sufficient distance to overlie the furring pieces of similar adjacent sheets of building material.
6. Building material comprising a backing member sufficiently stiff to constitute the siding of a building, said backing member being provided with lath means, said lath means comprising furring pieces extending across said backing member and beyond the boundary of said backing member whereby to overlie an adjacent similar backing member.
7. Building material comprising a sheet of backing member, said sheet being sufficiently stiff to constitute the siding of a building, lath means attached to said backing member, said lath means comprising furring pieces extending across said sheet of backing member and beyond one boundary thereof whereby to overlie a similar sheet of backing member, said furring pieces having mounted thereon cross wires extending beyond the boundaries of said sheet
- a sufficient distance to overlie furring pieces on similar adjacent sheets.
8. Building material comprising a sheet of backing material, said backing material being sufficiently stiff to resist the pressure used in applying plaster thereto, said backing member being provided with lath means having furring functions permanently attached thereto, said building material being imperforate, whereby to have good insulating qualities.
9. In combination, the upright scantlings of a house, and building material mounted upon said scantlings, said building material comprising relatively stiff corrugated board means consisting of corrugated material faced on both sides with flat facing sheets, said corrugations extending at right angles to said scantlings, said corrugated board means having lath means permanently secured thereto on one side thereof.
10. Building material, comprising a sheet of backing material, said backing material being sufficiently stiff to resist the pressure used in applying plaster thereto, said backing member being provided with lath means permanently attached on one side thereof, said lath means comprising furring portions adapted to hold the remaining portions of said lath means in a spaced position relative to said backing member whereby plaster may securely grip said lath means.
11. Building material, comprising a backing member sufficiently stiff to resist the pressure used in applying plaster thereto, said backing member being provided with lath means, said lath means extending beyond the boundary of said backing member whereby to overlie an adjacent similar backing member to provide a reinforcement for plastic material along said boundary.
12. Building material comprising a backing member having lath means permanently secured thereto on one side thereof, said backing member comprising corrugated board having flat facing sheets on both sides thereof to provide air spaces whereby said building material has good heat and sound insulating functions, said corrugated board having the requisite stiffness to withstand the pressure used in applying plaster thereto.

Signed at Chicago, Illinois, this 7th day of March, 1922.

ROY G. BACHMAN.
